UNITED STATES PATENT OFFICE.

JAMES LONG, OF COVENTRY, ENGLAND.

BUILT-UP CUTTING TOOL.

1,408,706.

Specification of Letters Patent.

Patented Mar. 7, 1922.

Application filed December 22, 1919. Serial No. 346,658.

To all whom it may concern:

Be it known that I, JAMES LONG, a subject of the King of England, residing at Coventry, in the county of Warwick, England, 5 have invented certain new and useful Improvements in Built-Up Cutting Tools, of which the following is a specification.

This invention relates to built-up milling cutters, reamers, and the like of the type in 10 which the body portion is provided with longitudinally disposed grooves in which the cutters are held and have contact with their side and bottom portions, and it has for its principal object to provide improved 15 means for securing the blades in the bodies of the cutters, and, in the case of reamers, to provide for appropriate movement of the blades in the bodies to constitute an adjustable or expandible cutting tool.

20 According to this invention the body of the cutter has formed in it grooves of uniform dovetail cross-section, (the wider portion nearest the centre of the body), that is to say, grooves whose bottom edges are parallel to one another and whose sides are of a constant width apart along lines parallel 25 with their bottom edges, and in these grooves the cutters are held by a wedge-action. Where it is desired to secure the cutter 30 against movement or subsequent adjustment, such wedge action may be obtained by giving the cutter throughout its length only such a degree of taper as is required to ensure a driving fit in the groove.

35 For an adjustable reamer the depth of the grooves progressively increases from the end of the reamer body, and a wedge is employed side by side with the cutter and is adjustable lengthwise of the groove, the combined 40 cross section of cutter and wedge being such as to fit the groove uniformly from end to end. Upon the end faces of the cutters and wedges collectively, bears (preferably by the agency of a washer), an adjusting nut, 45 screw threaded upon the body of the reamer. By this arrangement the adjusting means are confined to one end of the reamer so that at the other end the cutters can project from the body clear of all obstructions to constitute 50 an end or bottom reamer.

The manner of carrying out the invention as applied to an adjustable reamer is shewn in the accompanying drawings, in which,—

55 Figure 1 is a side elevation,

Figure 2 is a central longitudinal section through the body of the reamer,

Figure 3 is an end elevation on a larger scale than the foregoing views,

Figure 4, also to a larger scale, shews a plan of the combined cutter and wedge, of 60 which

Figure 5 is an end view, and

Figure 6 shews a perspective view of a modified detail of construction.

Like letters indicate like parts throughout the drawings.

Formed in the parallel sided body A of the reamer are longitudinally disposed grooves A² adapted to receive the cutters B and wedges C. The depth of these grooves 70 A² uniformly increases from end to end, as shewn in Figure 2, their sides converging to one another at the upper part of the groove to give to it a dove-tail cross section.

It is to be understood that in forming 75 these grooves their cross-section is, with reference to their bottom surface, uniform from end to end, that is, their bottom edges are parallel to one another and their sides are of a constant width apart along any lines 80 parallel to their bottom edges, but, obviously, by reason of their gradually increasing depth, the width at the upper edges of the grooves (as seen in Figure 1) diminishes as the depth of the grooves A² increases. 85

The manner of forming the grooves A² is preferably such that the angle X° which each side of the groove makes with the contiguous part of the bottom is a right angle. This not only facilitates fitting the cutters B and 90 wedges C in the grooves, but also avoids the necessity for a cutting-tool of special form, it being thus possible to use an ordinary sides-and-face type milling cutter in the manner hereunder described, which thus 95 gives rise to the particular form (i. e., a flattened V form) of the bottom of the groove as shewn in the drawings. Obviously, however, if desired the bottom of the grooves A² might be an entirely flat surface and the 100 angle X° at which the sides meet it might be varied from the foregoing value according to convenience of manufacture.

In a convenient method of manufacture, the groove is first formed of rectangular 105 cross-section by a milling cutter as above whose periphery cuts the bottom part of the groove. A further cut is then made with the same tool, after resetting the reamer body in the machine so that one of the side walls of the groove just formed will be recut to constitute with the opposite side of the

groove a dove-tail cross section. As a result of this, the finished groove A^2 has two faces at the bottom part, inclined to one another but each at right angles to its adjacent 5 side of the groove. In cross-section one side of the groove is substantially parallel to a radial line extending from the centre of the reamer body to a position midway between the top edges of the groove, while the other 10 side of the groove is inclined considerably to the radial line aforesaid. Against this latter side and the adjacent bottom surface of the groove the respective faces B^2 and B^3 of the cutter B, which has in all four faces, closely 15 fit. Preferably some clearance (not shewn) is provided between the next face B^4 of the cutter and the adjacent face of the bottom of the groove, so that only the right-angled surfaces B^2 , B^3 require fitting.

20 The last face B^5 of the cutter is adapted to co-operate with the inclined face C^2 of the wedge C, (which latter is of rectangular cross-section), in such manner that when the cutter B and wedge C are together inserted 25 in the groove A^2 they bear upon the bottom thereof and closely fit the sides from end to end of the groove.

It will be seen by reference to the drawings that the action of the wedge C is to 30 thrust the cutter B firmly against the side and bottom of the groove A^2 and the clearance given to the side B^4 of the cutter, as above mentioned, ensures this action taking place.

35 The edge B^6 of the cutter B stands above the edges of the groove A^2 to form the cutting edge of the reamer, and the wedge C is adjustable lengthwise of the groove.

The inner end of the reamer body A is 40 reduced somewhat in diameter and is screw-threaded over a portion A^3 of the so reduced part, the remaining part A^4 between the screw-threaded part and the body A being left plain. The grooves A^2 are prolonged 45 into this screw-threaded part A^3 , and the cutter B and wedge C are of a length to extend beyond the end of the plain part A^4 into the screwed part A^3 , by an amount 50 equal to that required for their range of adjustment lengthwise.

The inner ends of the cutters and wedges are squared off so that they can be uniformly 55 acted upon by an adjusting nut D carried upon the screw-threaded part A^3 and provided with slots D^2 or the like by which it can be rotated, a washer or collar E being inserted between the co-operating faces of the nut and cutters. To prevent rotation of the collar E during adjustment of the nut D, 60 slots E^2 or the like may be provided for engagement by a spanner, or if desired, a pin or feather might be provided on the inner periphery of the washer to engage a groove in the reamer body.

65 It will be apparent that when the reamer

is adjusted by the longitudinal movement of the cutters, their cutting radius will be increased in accordance with the longitudinal inclination of the bottom of the groove to the axis of the reamer.

70

As the adjustment acts positively in one direction only, that is to increase the cutting radius, it is evident that adjustment in the reverse direction can be accomplished by simply slackening back the nut D as far as 75 required and tapping on the outer ends of the cutters and wedges to return them against the face of the collar E.

By means of the wedge C any required degree of tightness of fit of the cutter B can be 80 obtained in the groove A^2 . As the latter is of uniform section throughout its length, no change in the fit will take place during adjustment of the reamer, provided no relative movement of cutter and wedge occurs 85 during such adjustment. Such relative movement is avoided by accurately squaring off the inner ends of the cutter and wedge after the latter have been adjusted to a correct fit in the groove, so that they may both 90 move together under the action of the nut D.

An important feature in this method of fitting the cutters is the ability to take up, by means of the wedge, any slackness of the 95 cutter due to prolonged wear. After such adjustment for wear it will be obvious that the end surfaces of the cutter and wedge must again be made flush with one another, as when originally squared off in the first instance. In inserting the wedge and cutter 100 in the groove it is obviously preferable that the thin end of the wedge should be towards the adjusting nut D so that after adjustment the wedge, instead of the cutter requires facing off.

105

To prevent the wedges being drawn from the grooves, if the reamer grips fast in use and has to be pulled endwise to free it, screws F may be sunk in the body A, to engage with their heads the elongated notches 110 C^3 formed in the outer edge of the wedges C. This screw F would require to be slackened back somewhat when the reamer was expanded to allow for the resultant rise of the wedge in the groove.

115

If desired, in place of the plain collar or washer E, the modified form, G, Figure 6, may be employed. This is provided with projections G^2 adapted to enter the grooves A^2 thus preventing its relative rotation on the reamer. These projections G^2 may also be extended at G^3 from one of the end faces of the collar to bear on the ends of the cutters and wedges, their length being made equal to the amount of the longitudinal adjustment provided for the cutters B. By this arrangement only the threaded part A^3 of the reamer body need be reduced below the diameter of the body A, and thus the parts of the cutters which would otherwise 120

125

130

lie in the reduced part A* (see Figure 1) can be as well supported as those portions which lie in the part A.

A special feature of this adjustable 5 reamer is that the adjusting means are confined to one end of the cutter, so that at the other end the cutters can project from the body clear of all obstruction, to constitute an end or bottoming reamer.

10 Furthermore, it will be apparent that by this invention the cutter can be firmly secured along the whole length of the groove by means which are entirely independent of the adjusting device, and that these means 15 ensure the cutter being always thrust against the bottom of its groove, a condition essential to precise adjustment.

By reason of the wedge section of the cutters, those parts which project from the end 20 of the body possess great lateral stiffness so that the tendency of their cutting-edges to chatter is thereby minimized.

Where the invention is applied to built-up 25 milling cutters or the like, the cutters may be firmly secured by means of wedges employed on the grooves as above described. Alternatively, the wedges may be omitted, by fitting the cutters to the grooves and giving to the former just sufficient taper to 30 ensure a driving fit to locate it in position.

What I claim as my invention and desire to secure by Letters Patent is:—

1. A reamer comprising a body part having cut lengthwise therein a groove of uniform cross section with a wide bottom, one 35 of the side walls of the groove being parallel to a radial line extending from the center

of the said body part midway between the top edges of said groove and the other side wall being inclined to the said radial line, 40 the angles formed by the said side walls with their contiguous bottom part being both right angles; the cutter closely fitting the one side wall and bearing on the bottom of the said groove. 45

2. In a reamer as specified in claim 1, a wedge arranged adjacent the straight side wall between the latter and the corresponding straight side of the cutter, the combined cross-section of the said cutter and wedge 50 being uniform and fitting the two sides of the groove from end to end.

3. A reamer as specified in claim 1, in which between the cutter and the other side wall a wedge is arranged and in which 55 the groove progressively inclines toward the cutter-axis from the forward end of the body part toward its rear end, the body part having a reduced portion where the groove approaches the cutter-axis, the cutter and 60 wedge protruding from the groove beyond said reduced portion, and an adjusting nut being screw-threaded on the said reduced portion so as to bear on the ends of both the cutter and wedge and act thereon simultaneously. 65

In testimony whereof I have signed my name to this specification in the presence of two subscribing witnesses.

JAMES LONG.
